PORTABLE FLASHLIGHT

Adolph C. Recker, Watertown, Conn., assignor to
The Chase Companies, Incorporated, Water-
bury, Conn., a corporation

Application October 11, 1934, Serial No. 747,840

1 Claim. (Cl. 240—10.68)

This invention relates to an improvement in portable flashlights and particularly to portable tubular flashlights which have a control-plunger at one end and an electric bulb at the other and 5 primarily designed for convenient carriage in the pocket of a user, though not so limited.

One of the objects of the present invention is to provide a flashlight having a control- or contact-plunger at one end and characterized by 10 surety of operation and freedom from derangement.

A further object is to provide a superior flashlight of the character referred to which may be readily and conveniently assembled.

15 Another object is to provide a flashlight of the character referred to which may be produced at low cost for manufacture.

With the foregoing and other objects in view, as will appear to those skilled in the art from the following, considered in conjunction with the accompanying drawing and appended claim, the present invention includes all features disclosed 20 therein which are novel over the prior art.

In the accompanying drawing:

25 Fig. 1 is a view in side elevation of a portable flashlight constructed in accordance with the present invention;

Fig. 2 is a broken central-longitudinal sectional view thereof;

30 Fig. 3 is a broken central-longitudinal sectional view, showing the contact-plunger depressed;

Fig. 4 is a transverse sectional view taken on the line 4—4 of Fig. 3;

35 Fig. 5 is a view mainly in side elevation and partly in section of the unit comprising the contact-plunger and guide-skirt;

Fig. 6 is a view mainly in side elevation and partly in longitudinal section of the socket; and

40 Fig. 7 is an end view thereof.

The portable flashlight herein chosen as illustrative of the present invention comprises a tubular body-member 10 having one end inturned to form an annular stop-lip 11 and having its opposite end 12 threaded and fitting within the threaded outwardly-expanded skirt 13 of an end-cap 14, which latter, together with the said body-member 10, constitutes a flashlight-housing or body.

50 The domical outer end of the end-cap 14 is provided with an aperture 15 through which normally projects the outer end of an axially-reciprocating contact-plunger 16 housed mainly within the said end-cap and adapted to have its inner end engaged with the adjacent end of an

electric cell 17, two (more or less) of which latter are housed within the tubular body 10 before referred to. The parts above described are preferably formed of brass or other suitable conducting material for the purpose as will hereinafter appear. 5

The electric cell adjacent the threaded end of the tubular body 10 rests against a washer-like seat 18 formed of insulating material, such as indurated fiber, and in turn resting against an annular shoulder 19 formed at the junction of the tubular rear portion 20 of the end-cap 14 and its expanded threaded skirt 13.

Bearing against the rear face of the seat 18 above referred to is the enlarged forward end of a helical retracting-spring 21 having its outer end, which is of smaller diameter than its inner end as shown, fitted within the interior of a sheet-metal guide-skirt 22 snugly fitting, with freedom for sliding movement, the interior of the tubular portion 20 of the end-cap 14. The domical outer end of the said guide-skirt 22 bears against an abutment-flange 23 formed on the contact-plunger 16 adjacent the outer end thereof, and the said guide-skirt is rigidly secured to the contact-plunger 16 by being provided with an inturned flange 24 fitting the contact-plunger 16 with a drive-fit. 25

Bearing against the inner face of the inturned stop-lip at the forward end of the tubular body-member 10 is an electric bulb 25 having its threaded portion 26 screwed into the threaded portion 27 of a socket-member 28 formed with three (more or less) rearwardly-extending retaining-fingers 29, each of which terminates at 35 its rear end in a hump portion 30 to better grip the interior surface of the forward end of the tubular body 10, which latter is preferably of serrated form in transverse section, as shown. 30

In assembling the flashlight, the bulb 25 is 40 first screwed into the threaded portion 27 of the socket 28, which latter, together with the bulb 25, is forced into the tubular body 10 from the open rear end thereof until the said bulb 25 engages with the inner face of the stop-lip 11. The 45 electric cells 17 may now be installed in the tubular body.

The end-cap 14 is prepared for application to the body-member 10 by first sliding the unit comprising the contact-plunger 16 and its guide-skirt 22 inward through the open end of the cap, so as to project the end of the contact-plunger outwardly through the aperture 15. The retracting-spring 21 may now be installed, after which the washer-like seat 18 is placed in the said 55

cap. Preferably, the washer-like seat 18 is of such size as to require it to be forced inward against the shoulder 19 of the cap, so as to semi-permanently retain the retracting-spring 21, contact-plunger 16 and its skirt 22 in place within the cap against accidental displacement therefrom when the cap is detached from the tubular body-member 10.

After the parts 16, 18, 21 and 22 have been assembled within the cap, the latter may be screwed over the threaded rear end of the tubular body 10, so as to bring the washer-like seat 18 into engagement with the outer end of the rearmost one of the electric cells 17 and thus 15 force the column thereof forwardly to engage the terminal of the foremost of said cells with the rearwardly-projecting terminal of the bulb 25.

Now, when it is desired to energize the bulb 25, the contact-plunger 16 may be moved inward- 20 ly by means of its projecting outer end against the tension of the retracting-spring 21, with the effect of correspondingly moving the guide-skirt 22 and projecting the inner end of the said contact-plunger 16 forwardly through the relatively-large aperture in the seat 18 and into engagement with the rearmost one of the electric cells 17. By the operation just described, an electric circuit is completed which serves to energize the bulb 25. Upon release of pressure 25 upon the rear end of the contact-plunger 16, the same will be retracted by means of the retracting-spring 21 with the effect of breaking the circuit through the bulb 25.

The provision of the contact-plunger 16 with 30 a hollow guide-skirt within which the retract-

ing-spring fits serves to insure the proper guidance of the said plunger and the closing of the circuit when the said plunger is depressed, without, however, unduly lengthening or laterally expanding the structure to accommodate the 5 parts.

The invention may be carried out in other specific ways than that herein set forth without departing from the spirit and essential characteristics of the invention, and the present 10 embodiment is, therefore, to be considered in all respects as illustrative and not restrictive, and all changes coming within the meaning and equivalency range of the appended claim are intended to be embraced therein. 15

I claim:

A flashlight comprising a tubular body-member having one end threaded; an electric bulb at the end of the said body-member opposite its threaded end; a cap secured to the end of 20 the said body-member opposite the said bulb and comprising a cylindrical portion at its outer end and an expanded threaded skirt at its inner end engaged with the threaded end of the said body-member; a ring-like spring-seat of insulating material located at the junction-point of the cylindrical outer end of the said cap and its expanded threaded skirt; a contact-plunger projecting through the outer end of the said cap and having a guide-skirt bearing therein; 25 and a retracting-spring fitting within the said guide-skirt and acting to outwardly press the said contact-plunger and its said guide-skirt. 30
